[57] CLAIM

The ornamental design for a check stand counter, as shown and described.

DESCRIPTION

FIG. 1 is a top plan view of a check stand counter showing my new design;

FIG. 2 is a front elevational view thereof;

FIG. 3 is a left side elevational view;

FIG. 4 is a rear elevation thereof;

FIG. 5 is a bottom plan view thereof; and,

FIG. 6 is a right side elevational view.

The broken lines shown throughout the views illustrate environmental structure and form no part of the claimed design.
